US00D699987S

(12) **United States Design Patent**
Angvall

(10) **Patent No.:** **US D699,987 S**
(b4) **Date of Patent:** **** Feb. 25, 2014**

(54) **DISPLAY STRUCTURE**

(75) Inventor: **Nicholas P. Angvall**, Minneapolis, MN
(US)

(73) Assignee: **Target Brands, Inc.**, Minneapolis, MN
(US)

(**) Term: **14 Years**

(21) Appl. No.: **29/415,549**

(22) Filed: **Mar. 12, 2012**

(51) LOC (10) Cl. **06-06**

(52) U.S. Cl.

USPC **D6/675.5**

CLAIM

(57) The ornamental design for a display structure, as shown and described.

DESCRIPTION

FIG. 1 is perspective view of a display structure;
FIG. 2 is a perspective view of the display structure of FIG. 1 with broken line subject matter removed;
FIG. 3 is a front view of the display structure of FIG. 1;
FIG. 4 is a back view of the display structure of FIG. 1;
FIG. 5 is a side view of the display structure of FIG. 1, the opposite side being a mirror image;
FIG. 6 is a top view of the display structure of FIG. 1; and,
FIG. 7 is a bottom view of the display structure of FIG. 1. The broken line subject matter forms no part of the claimed design.

1 Claim, 4 Drawing Sheets
